COMBINED CLOCK HOUSING AND DIAL FACE

Dario D'Adda, Viale Filippetti 33, Milan, Italy

Filed Aug. 14, 1972, Ser. No. 280,283

Term of patent 14 years

Int. Cl. D10—01

U.S. Cl. D10—26

FIG. 6

FIG. 5

FIG. 7

FIG. 1 is a front perspective view of a combined clock housing and dial face showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof;

FIG. 7 is a top plan view thereof.

I claim:

The ornamental design for a combined clock housing and dial face, as shown and described.
